UNITED STATES PATENT OFFICE.

BURNS D. LOCKWOOD, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

CAR-UNDERFRAME CONSTRUCTION.

1,167,769.

Specification of Letters Patent. Patented Jan. 11, 1916.

Application filed November 3, 1913. Serial No. 798,791.

To all whom it may concern:

Be it known that I, BURNS D. LOCKWOOD,
a citizen of the United States, residing at
141 Sprague avenue, Bellevue, in the county
5 of Allegheny and State of Pennsylvania,
have invented certain new and useful Im-
provements in Car-Underframe Construc-
tion, of which the following is a full, clear,
and exact description, such as will enable
10 others skilled in the art to which it apper-
tains to make and use the same, reference
being had to the accompanying drawings,
forming part of this specification.

An object of the present invention is to provide a railway car underframe that is light and strong and which can be manufactured at low cost, and which is especially adapted for use in box car construction, but which may be used in any other classes of cars where suitable.

Another object of the present invention is to reduce to a minimum the number of parts of which the underframe is composed, with a consequent reduction in the number of 25 curing means employed for connecting such parts.

30 A further object of the present invention is to provide a car underframe in which the bolster comprises a single element, extending preferably from side to side of the underframe and forming a connecting medium between the center and draft sills, the bolster being provided with suitable portions to which the center sill and draft sill members are connected.

35. **35. Sills are connected.** A specific object of the present invention is to provide a bolster member which extends from side to side of the underframe, in the central portion of which is combined 40 the center brace, together with provision for receiving the king pin, and also a converging web portion suitable for connection to the center sill, and projecting portions to which the draft sills may be secured.

45 With these and other objects in view, the present invention consists in the combination and arrangement of parts, as will be hereinafter more fully described, shown on the accompanying drawings, and particularly pointed out in the appended claims; it being understood that changes in the form, proportion, size and minor details may be made, within the scope of the claims, without departing from the spirit or sacri-

ficing any of the advantages of the invention. 55

Referring now to the drawings, in which like reference characters refer to like parts and in which Fig. 1 is a plan view of a portion of an underframe embodying the invention; Fig. 2 is a sectional view taken on the line 2—2 of Fig. 1; Figs. 3, 4 and 5 are cross sectional views on the lines 3—3, 4—4 and 5—5 respectively of Fig. 1, and Fig. 6 is an enlarged detail sectional view on the line 6—6 of Fig. 2. 60 65

Referring now in detail to the drawings, 1 indicates the center sill which may be of rolled I beam section, or as shown in the several figures of the drawings, may be built up of commercial bars and plates. 2 indicates the web to which are secured the top or compression bulb angles 3, 3 and the bottom or tension angles 4, 4.

5 indicates the bolster member which comprises a single element preferably of I form in cross section for a greater part of its length. The outer ends of this bolster member are provided with flanges 6, 6, to which the side sills 7, 7 are secured. Beyond the side sills these outer ends are provided with extension portions 8, 8, the undersides of which form bearing surfaces for jacks when it is desired to lift the car from its trucks. 75 80

These extension portions are provided with openings 9, 9, through which a rope may be passed when it is desired to shift the car by such means. From a point on either side of the longitudinal center line of the car, the web portions 10, 10 of the bolster 5 converge toward said center line in a direction toward the transverse center line of the car, and on the opposite side is provided with lugs 11, 11, to which the draft sills 12, 12 are secured, such draft sills being also secured to the end sill 13 by any suitable means. These lugs and converging portion of the bolster are strengthened by the vertical rib 14, the horizontal ribs 15, top flanges 16, 17 and by the bottom flanges 18, 19. The top flange 16 and the bottom flange 18 may be substantially alike, having portions to which the draft sills are secured. The top flange 17 and the bottom flange 19 may be substantially alike, and have portions 20 to which the tension and compression members of the center sill are secured. To form a more rigid connection between the center

sill and the bolster, members 21, 21 of any suitable form are provided which are riveted or otherwise secured to both the bolster and the center sill.

5 The cross beams 22 are preferably of rolled form and extend from side to side of the car, the end portions forming seats for the side sills 7. Where the crossbeam passes through the web of the center sill, bracket 10 members 23, 23 are provided which are secured to said cross beam and web.

In the several drawings, only one end of the underframe has been shown, but it will be understood that the other end is substantially the same in all respects.

Having thus described the invention what I claim as new and desire to secure by Letters Patent is:—

1. An underframe comprising a single 20 rigid bolster element in combination with a single center sill, said bolster element having a central V-shaped portion to which the end of said center sill is secured.

2. An underframe comprising a single 25 rigid bolster element in combination with a single center sill, said bolster element having a wedge shaped web portion intermediate its ends, and means connecting said center sill and wedge shaped web portion.

3. In a railway car underframe, the combination with a single bolster element having a wedge shaped web portion intermediate its ends, of a single center sill framed into said bolster element, and means for 35 connecting said members.

4. In a railway car underframe, the combination with a single bolster element having a V-shaped web portion of a single center sill framed into said bolster member and 40 means secured to said sill and V-shaped portion for connecting all of said members.

5. In a railway car underframe, the combination with a single rigid bolster element having lugs extending in one direction, and 45 a central V-shaped portion extending in the opposite direction, of draft sills secured to said lugs and a single center sill secured to said V-shaped portion.

6. An underframe comprising a single 50 rigid bolster element in combination with a single center sill and a pair of draft sills, said bolster element having a V-shaped web portion.

7. In a railway car underframe, the combination with a single rigid bolster element having a wedge shaped portion and lugs intermediate its ends, of draft sills secured to 55 said lugs, a single center sill and means for securing said center sill to said wedge shaped portion of said bolster.

8. A bolster of substantially I shape in cross section having a wedge shaped web

said bolster, and longitudinal sills secured to said lugs.

9. A bolster of substantially I shape in cross section having a wedge shaped web portion intermediate its ends, lugs projecting from the web of said bolster, and draft sills secured to said lugs.

10. A bolster of substantially I shape in cross section having, intermediate its ends, a wedge shaped web extending in one direction and lugs extending in the opposite direction, a center sill connected with said web, and draft sills secured to said lugs.

11. A bolster of substantially I shape in cross section having a wedge shaped web portion intermediate its ends and means for strengthening said wedge shaped web portion, a center sill, and means for connecting said web and sill together.

12. A bolster of substantially I shape in cross section having a wedge shaped web portion intermediate its ends and ribs for 85 strengthening said wedge shaped web portion, one of said ribs having an opening formed therein for the reception of a king pin, a center sill, and means for connecting said web and sill together.

13. In a railway car underframe, the combination with a bolster having a V shaped web portion intermediate its ends, a center sill terminating short of said V shaped web portion, and angular members connecting 95 said center sill and V shaped web portion.

14. In a railway car underframe, a bolster member having a V shaped web portion intermediate its ends, said V shaped web portion extending in a direction toward 100 the transverse center line of the underframe, lugs extending from said web portion in a direction toward the end of the underframe, draft sills secured to said lugs, a center sill terminating short of said V 105 shaped web portion, and angular members adapted to connect said sill and web portion.

15. In a railway car underframe, a bolster having a vertical web and horizontal top and bottom flanges on each side of said web, lugs projecting from said web, draft sills terminating short of said web and secured to said lugs and horizontal top and bottom flanges on one side of the web, 110 the center sill terminating short of said web and secured to said top and bottom flanges of the other side of said web, and angular members connecting said center sill and web of said bolster.

In testimony whereof I affix my signature in presence of two witnesses.
